UNITED STATES PATENT OFFICE.

GEORGE M. SPENCER AND CHRISTOPHER J. GRELLNER, OF ST. LOUIS,
MISSOURI.

DOUBLE-ACTING EQUALIZING-CYLINDER FOR FLUID-PRESSURE SYSTEMS.

SPECIFICATION forming part of Letters Patent No. 772,842, dated October 18, 1904.

Application filed October 5, 1903. Serial No. 175,739. (No model.)

To all whom it may concern:

Be it known that we, GEORGE M. SPENCER and CHRISTOPHER J. GRELLNER, citizens of the United States, residing in the city of St. Louis, in the State of Missouri, have invented certain new and useful Improvements in Double - Acting Equalizing - Cylinders for Fluid - Pressure Systems, of which the following is a full, clear, and exact description, reference being had to the accompanying drawings, forming part of this specification.

Our invention relates to a cylinder for fluid-pressure apparatus in which double action is furnished and in which the fluid-pressure against the piston therein is rendered equal or approximately equal at both sides of said piston in order that when the piston has been actuated in one direction the pressure medium may be equalized in the cylinder at both sides of the piston and will have the same effect against both of its faces to equalize it. The cylinder is of particular utility in connection with that class of fluid-pressure brake systems set forth in our application for Letters Patent of the United States, filed June 25, 1903, Serial No. 162,997.

Our invention consists in features of novelty hereinafter fully described, and pointed out in the claims.

Figure I is a longitudinal section of our double-acting equalizing-cylinder. Fig. II is a cross-section taken on line II II, Fig. I. Fig. III is a cross-section taken on line III III, Fig. I.

1 designates a cylinder proper that at one end is closed by a head 2, preferably furnished with a pocket extension 3. At the opposite end the cylinder is closed by a head 4, that bears a tubular extension 5, containing an enlarged cavity 6.

7 is a pressure-medium pipe leading to and seated in the cylinder-head 4, and 8 is a pressure-medium pipe seated in the cylinder-head 2 and leading therefrom. The pipe 7 leads to the cylinder from a source of supply of pressure medium to deliver such medium into the cylinder, and the pipe 8 leads from the cylinder to a point of discharge to conduct the pressure medium from said cylinder, and

both of said pipes are brought into coinciding 50 relation with each other, so that they may have communication similar to that described in our application hereinbefore referred to with reference to the equalizing-pipes connected to the cylinder therein. 55

9 designates a piston that operates in the cylinder 1 and to one side of which is connected a tubular stem 10, which operates through the cylinder-head 2 and is encircled by suitable piston-rod packing 11. 60

12 is a piston-rod extending through the tubular system 10 and having bearing at its inner end against the piston 9. This piston-rod is separated from the tubular stem sufficiently to furnish a space between said members that has communication with a duct 13 in the piston 9. The piston-rod 12 receives the connection of a brake-lever, as seen at 14, Fig. I, or any other member to which it may be desired to communicate motion. 70

15 designates a second tubular stem secured to the piston 9 at its opposite side from that to which the stem 10 is secured. This stem 15 extends through the cylinder-head 4 and a suitable packing 16 and operates in the tubular extensions 5, carried by said cylinder-head. 75

17 designates a spring surrounding the tubular stem 10 and positioned between the piston 9 and the cylinder-head 2, its outer end 80 being preferably located in the pocket extension of said cylinder-head, as seen in Fig. I. This spring is designed for service in returning the piston 9 to the high-pressure-receiving end of the cylinder 1, to which the pressure medium of pipe 7 leads, the spring being brought into service after the piston 9 has completed its forward stroke and the pressure medium in the cylinder at both sides of the piston has been equalized. 85

In the practical use of our cylinder pressure medium, such as air under heavy pressure, is conducted to the cylinder through the pipe 7 and on entering the cylinder at the rear side of the piston therein acts against the piston to effect its forward stroke and carry the piston-rod 12 in a corresponding direction to actuate the brake-lever or other mem- 95

ber connected thereto. During the forward stroke of the piston the spring 17 is compressed and at the same time the tubular stem 15 is carried forwardly with the piston and 5 by its presence in the cylinder-space compensates for the difference in displacement of pressure medium at opposite sides of the piston that would be present in the instance of the employment of the piston-rod 12 alone or said 10 piston-rod and the tubular stem 10 surrounding it. It will therefore be seen that equal pressure surfaces at both sides of the piston are furnished and that therefore pressure medium at either of its sides may act there- 15 against with uniform driving power, owing to the equal area of piston-surfaces afforded to the pressure medium. After the piston has made its forward stroke, as stated, the pressure medium in the cylinder is equalized 20 at opposite sides of the piston by furnishing communication from the pipe 7 to the pipe 8 in any suitable manner, such as that described in our application for patent hereinbefore referred to, and when such communication is 25 established the pressure at the rear of the piston will be in part transferred to the forward side of the piston and the pressure thus equalized at the two ends of the cylinder. As soon as this equalization has been secured the 30 spring 17 comes into action and effects return stroke of the piston 9. This it is permitted to do by reason of the presence of the tubular stem 15, located at the rear side of the piston, which offsets the displacement in 35 the cylinder at the rear side of the piston to a degree corresponding to the displacement incurred by the presence of the piston-rod at the forward side of the piston.

The space furnished between the piston-rod 40 12 and tubular sleeve 10 and the duct 13 in the piston 9 are provided for the purpose of furnishing communication between the cavity 6 in the tubular extension 5, in which the stem 15 operates, and the exterior of the cylinder 45 in order that there may be constant circulation of air into and from said cavity to prevent the formation of air-cushion or vacuum therein.

While we have described in connection with 50 our construction of double-acting and equalizing cylinder the stems 10 and 15 as furnishing means through which the displacement at opposite sides of the piston in the cylinder is rendered equal and the spring 17 for causing 55 return stroke of the piston, we do not wish to be limited to the precise arrangement set forth nor to the use of the spring for causing return stroke of the piston. In this connection we would mention that instead of making 60 use of the spring the displacement member at the side of the piston at which said spring is located may be of a less size than the displacement member at the opposite side of the piston and the spring dispensed with, in which 65 case there would be a greater pressure-receiv-

ing area at the forward side of the piston for the pressure medium to act against when equalizing in the cylinder, and therefore the same action against the piston be furnished as where the spring is used. It is also evident that the piston in the cylinder may be actuated to exert a pull upon the piston-rod instead of pushing it, and in such instance the displacement member at the rear side of the piston may be of less diameter than the displacement member at the forward side to gain the same action as that just previously referred to.

While we have described the displacement member 15 as a tubular stem, it is obvious 80 that displacement members of other forms may be used—such, for instance, as a flexible member, in the use of which a vent to avoid cushion or vacuum in the part in which the displacement member operates may be dispensed with.

While we have described the vent from the tubular extension in which the displacement-stem 15 operates as furnished from said stem through the duct 13 and through the tubular piston-rod-inclosing stem 10, it is obvious that this vent may be furnished in any other suitable manner, such as by placing a duct in the tubular extension 5.

We claim as our invention—

1. A fluid-pressure cylinder having means therein for approximately equalizing the action of pressure medium at both faces of the cylinder-piston, and means exterior of said cylinder for admitting pressure medium into 100 each end of the cylinder, substantially as set forth.

2. The combination with a fluid-pressure cylinder proper and piston therein, of means in said cylinder for rendering the displacement of pressure medium approximately equal at both sides of said piston, and means exterior of said cylinder for admitting pressure medium into each end of the cylinder, substantially as set forth.

3. The combination with a fluid-pressure cylinder proper and piston therein, of members carried by said piston by which the displacement of pressure medium at both sides of said piston is rendered approximately equal, and means exterior of said cylinder for admitting pressure medium into each end of the cylinder, substantially as set forth.

4. The combination with a fluid-pressure cylinder proper and piston therein, of members carried by said piston by which the displacement of pressure medium at both sides of said piston is rendered equal or approximately equal; and means exterior of said cylinder for admitting pressure medium into each end of the cylinder, said cylinder being provided with a vent communicating with the exterior air to avoid the presence of cushion or a vacuum in a part in which a displacement member operates, substantially as set forth.

5. The combination with a fluid-pressure cylinder proper and piston therein, of a piston-rod at one side of said piston to be operated thereby, a pressure-medium-displacing stem carried by said piston at the side opposite to that at which said piston-rod is located, and means exterior of said cylinder for admitting pressure medium into each end of the cylinder, substantially as set forth.
10. 6. The combination with a fluid-pressure cylinder proper and piston therein, of a piston-rod at one side of said piston to be operated thereby, a tubular stem carried by said piston at the side opposite to that at which said piston-rod is located, and means exterior of said cylinder for admitting pressure medium into each end of the cylinder, substantially as set forth.
15. 7. The combination with a fluid-pressure cylinder proper and piston therein, of means for equalizing the pressure-medium-contacting space against said piston, a spring acting against said piston at one side thereof, and means exterior of said cylinder for admitting pressure medium into each end of the cylinder, substantially as set forth.
20. 8. The combination with a fluid-pressure cylinder proper and piston therein, of a piston-rod at one side of said piston, a tubular stem surrounding said piston-rod and connected to said piston, and a tubular stem connected to said piston at the opposite side to that at which said piston-rod and first-named tubular stem are located, substantially as set forth.
25. 9. The combination with a fluid-pressure cylinder proper and piston therein, of a tubu-

lar extension projecting from one of the heads of said cylinder, a tubular stem connected to said piston and operating in said tubular extension, and a piston-rod located at the opposite side of said piston to that at which said tubular stem is located, substantially as set forth.

10. The combination with a fluid-pressure cylinder proper and piston therein provided with a duct, of a tubular extension projecting from one of the heads of said cylinder, a tubular stem connected to said piston and operating in said tubular extension, a piston-rod located at the opposite side of said piston from that at which said tubular stem is located, and a tubular stem surrounding said piston-rod and connected to said piston, substantially as set forth.

11. The combination with a fluid-pressure cylinder proper and piston therein, of an extension projecting from one of the heads of said cylinder, a stem connected to said piston and operating in said extension, a piston-rod located at the opposite side of said piston from that at which said stem is located, a tubular stem surrounding said piston-rod and connected to said piston, and a spring surrounding said piston-rod and tubular stem and bearing against said piston, substantially as set forth.

In testimony whereof we have hereunto set our hands this 25th day of September, 1903.

GEO. M. SPENCER.

CHRISTOPHER J. GRELLNER.
